COILING SILICON STEEL STRIP

John M. Felton, Wellsburg, W. Va., and Clarence H. Verwohlt, St. Clairsville, Ohio, assignors to Wheeling Steel Corporation, Wheeling, W. Va., a corporation of Delaware

Application April 10, 1951, Serial No. 220,247

5 Claims. (Cl. 29—470)

1

This invention relates to coiling stiff strip. It has to do with controlling stiff strip as it passes to the reel upon which it is being coiled whereby to insure the formation of a straight, even coil. The invention further relates to the coiling of strip which is subject to tearing under heavy tension and to the treatment of such strip as it is being coiled to render it less subject to tearing.

While our invention is of broad utility it has especial usefulness in the coiling of silicon steel strip and particularly in the forming of strip out of stiff sheets or sheets of material subject to tearing under heavy tension such as sheets of silicon steel and coiling the strip thus produced. For purposes of explanation and illustration the invention will be described in connection with the forming of strip out of silicon steel sheets and the coiling of such strip.

Silicon steel in sheet or strip form is very stiff and subject to tearing under heavy tension. Because of its stiffness it cannot be coiled in the conventional way. The strip does not form uniformly into a coil but tends to weave back and forth in the direction of the axis of the coil, forming an uneven and commercially unsatisfactory coil. Various proposals of special ways to coil silicon steel strip have been made but none has been fully satisfactory. We have found the solution to the problem.

We coil silicon steel or other stiff strip by feeding the strip to a reel, rotating the reel to coil the strip and during such rotation of the reel engaging the strip and pulling backwardly thereon whereby the strip is coiled under heavy tension, insuring formation of a straight, even coil. While we prefer to coil the strip continuously we may when required rotate the reel intermittently to periodically coil portions of the strip and during each period during which the reel is being rotated engage the strip and pull backwardly thereon and during each period during which the reel is not being rotated maintain the strip leading to the reel under heavy tension so that the strip is maintained at all times under heavy tension.

As indicated above, our invention has especial usefulness in the forming of strip out of stiff sheets and coiling the strip. We preferably successively bond stiff sheets end-to-end to form strip and lead the strip to a reel, rotate the reel to coil the strip and during such rotation of the reel engage the strip and pull backwardly thereon whereby the strip is coiled under heavy tension.

Also, we coil strip subject to tearing under heavy tension by coiling the strip under heavy

10 tension and as the strip passes to the coil subjecting it to a stress-relieving heat treatment to render it less subject to tearing.

In a preferred procedure we coil stiff strip subject to tearing under heavy tension by feeding the strip to a reel, rotating the reel to coil the strip, during such rotation of the reel engaging the strip at a tensioning station and pulling backwardly thereon, whereby the strip is coiled under heavy tension, and at the tensioning station subjecting the strip to a stress-relieving heat treatment to render it less subject to tearing. We may form strip out of sheets of stiff material subject to tearing under heavy tension and coil the strip by successively bonding end-to-end sheets of such material to form strip, leading the strip to a reel, rotating the reel to coil the strip, during such rotation of the reel engaging the strip at a tensioning station and pulling backwardly thereon, whereby the strip is coiled under heavy tension, and at the tensioning station subjecting the strip to a stress-relieving heat treatment to render it less subject to tearing.

15 We further provide apparatus for coiling stiff strip comprising a reel, means for rotating the reel to coil the strip and means engaging the strip and pulling backwardly thereon as the strip moves to the reel, whereby the strip is coiled under heavy tension, insuring formation of a straight, even coil. We may employ roll means 20 having a sufficiently large area of contact with the strip as the strip moves to the reel to enable the roll means to exert a strong frictional drag on the strip together with means tending to turn at least part of the roll means in such a direction as to draw the strip away from the reel whereby the strip is coiled under heavy tension. The roll means preferably comprises a tensioning roll about which the strip passes as it moves to the reel and a source of power is preferably connected with the tensioning roll tending to turn that roll in a direction to draw the strip away from the reel but permitting the tensioning roll to turn in the opposite direction due to the frictional pull exerted thereon by the strip as it is drawn by the reel.

25 We desirably provide means for holding in fixed position both the reel and the tensioning means to maintain the strip under tension when the reel is not rotating. We preferably provide two motors, one for rotating the reel to coil the strip and the other for operating the tensioning means in a direction to draw the strip away from the reel, and we desirably provide brakes

for both the reel and the tensioning means to maintain the strip under tension at all times.

We further provide apparatus for coiling strip subject to tearing under heavy tension comprising a reel, means for rotating the reel to coil the strip, means for maintaining the strip under heavy tension while it is being coiled and means subjecting the strip as it passes to the reel to a stress-relieving heat treatment to render it less subject to tearing. When we provide means engaging the strip and pulling backwardly thereon as the strip moves to the reel to coil the strip under heavy tension we desirably employ means in the region of the last mentioned means heating the strip to subject the strip to a stress-relieving heat treatment. A heated roll is found to serve the purpose very satisfactorily.

We also provide apparatus for forming strip out of stiff sheets and coiling the strip comprising bonding means for successively bonding stiff sheets end-to-end to form strip, a reel positioned to receive the strip directly from the bonding means, means for rotating the reel to coil the strip and means engaging the strip and pulling backwardly thereon as the strip moves to the reel, whereby the strip is coiled under heavy tension. When strip is to be formed out of sheets of stiff material subject to tearing under heavy tension we preferably employ bonding means for successively bonding such sheets end-to-end to form strip together with a reel positioned to receive the strip directly from the bonding means, means for rotating the reel to coil the strip, means engaging the strip and pulling backwardly thereon as the strip moves to the reel, whereby the strip is coiled under heavy tension, and means subjecting the strip as it passes to the reel to a stress-relieving heat treatment to render it less subject to tearing.

Other details, objects and advantages of the invention will become apparent as the following description of a present preferred embodiment thereof and a present preferred method of practicing the same proceeds.

In the accompanying drawings we have shown a present preferred embodiment of the invention and illustrated a present preferred method of practicing the same, in which

Figure 1 is an elevational view, partly in cross section, of apparatus for forming strip out of sheets and coiling the strip; and

Figure 2 is a plan view of the apparatus shown in Figure 1.

Referring more particularly to the drawings, there is shown at 2 a bonding or welding station where sheets are welded or otherwise bonded successively end-to-end to form strip. The sheets are advanced from the left toward the right, the leading end of each sheet being bonded to the trailing end of the preceding sheet so that a strip made up of sheets bonded together end-to-end is formed which is delivered to the right from the bonding station 2. The sheets are clamped in position for bonding by clamping means designated generally by reference numeral 3, the details of which do not constitute the present invention. The clamping means is claimed in our copending application Serial No. 220,246, filed April 10, 1951. There is shown a traveling welder head 4 which may be of conventional construction and which travels along the joint between the contiguous edges of the clamped sheets to weld the edges together. For purposes of explanation and illustration the sheets will be considered as being silicon steel

sheets so that the strip which moves toward the right from the bonding station 2 is silicon steel strip made up of sheets welded together. That strip is stiff so that it cannot be conventionally coiled and it is also subject to tearing under heavy tension. Special provision, therefore, has to be made for coiling the strip and since heavy tension must be employed in coiling provision must also be made for rendering the strip less subject to tearing.

The strip moves to the right from the bonding station through a drag wiper 5, about a pair of cooperating rubber covered bridle rolls 6, over a steel idler roll 7 and to a reel 8 where the strip is formed into a coil by turning of the reel. The reel 8 is driven by an electric motor 9 through a gear reduction unit 10 and a coupling 11. The reel may be provided with a coil stripper plate 12. The reel is provided with a brake, not shown, which becomes effective to hold the reel against turning when the motor 9 is deenergized.

The upper and lower rubber covered bridle rolls 6 constitute strip tensioning means and the location at which they and the idler roll 7 are disposed is a tensioning station. The upper roll 6 is an idler but the lower roll 6 is connected through a jack shaft 13 with an electric motor 14 which when energized tends to turn the lower roll 6 in the clockwise direction viewing Figure 1, i. e., in such a direction as to tend to draw the strip, designated by reference numeral 15, backwardly or toward the left away from the reel 8, whereby to apply heavy tension to the strip, insuring formation on the reel 8 of a straight, even coil. The lower roll 6 has a sufficiently large area of contact with the strip to enable the roll to exert a strong frictional drag on the strip, the upper roll 6 insuring maintenance of the strip in proper relation to the lower roll 6 to accomplish the result. Normally the motor 14 does not actually turn the lower roll 6 in the clockwise direction; on the contrary, despite the tendency of the motor 14 to turn the lower roll 6 in the clockwise direction that roll actually turns in the counter-clockwise direction due to the frictional pull exerted thereon by the strip as it is drawn by the reel. However, the motor 14 does insure maintaining the strip under heavy tension at all times. The torque exerted on the reel shaft by the motor 9 and its connections is somewhat greater than the torque exerted on the shaft of the lower roll 6 by the motor 14 and its connections so that the reel turns despite the efforts of the motor 14 to prevent it from turning. A brake 16 is applied to the shaft of the lower roll 6 and becomes effective when the motor 14 is deenergized.

When rotation of the reel 8 is to be stopped the motor 9 may be deenergized to such a degree that the motor will stand in a stalled condition thus maintaining tension on the strip continuously. The result is that the relatively stiff strip is maintained under heavy tension and a straight, even coil is formed on the reel.

The strip in addition to being stiff may also, as above indicated, be subject to tearing under heavy tension. This is true of silicon steel strip. We find it important to make provision for rendering the strip less subject to tearing. To that end we subject the strip as it passes to the reel to a stress-relieving heat treatment. While this may be done in various ways we find it desirable to heat one of the rolls in contact with which the strip passes at the tensioning station. For example, the steel idler roll 7 may be heated

as by electric heating elements disposed therewithin. The heat is transmitted through the surface of the roll to the strip. There is ample opportunity for the heat to penetrate the strip since the strip moves very slowly. The roll is heated to such a temperature that the strip as it passes over the roll will be given a low temperature stress-relieving anneal. The annealing temperature may be of the order of three or four hundred degrees Fahrenheit. This low temperature stress-relieving anneal renders the strip less subject to tearing so that it is not torn even under the heavy tension applied to it.

While we have shown and described a present preferred embodiment of the invention and a present preferred method of practicing the same it is to be distinctly understood that the invention is not limited thereto but may be otherwise variously embodied and practiced within the scope of the following claims.

We claim:

1. A method of forming a strip out of sheets of silicon steel comprising turning a partially formed coil of strip of previously bonded together sheets of silicon steel to continue formation of the coil, successively bonding additional sheets of silicon steel to the trailing end of the strip, while turning the coil exerting back tension on the strip between the trailing end of the strip and the coil and by said back tension alone causing the strip to form a straight, even coil.

2. A method of forming a strip out of sheets of silicon steel comprising intermittently turning a partially formed coil of strip of previously bonded together sheets of silicon steel to continue formation of the coil, successively bonding additional sheets of silicon steel to the trailing end of the strip, exerting on the coil (even when the coil is not being turned) a coiling force and exerting on the strip between the trailing end of the strip and the coil a force tending to inhibit coiling of the strip and by said forces alone causing the strip to form a straight, even coil.

3. A method of forming a strip out of sheets of silicon steel comprising intermittently turning a partially formed coil of strip of previously bonded together sheets of silicon steel to continue formation of the coil, successively bonding additional sheets of silicon steel to the trailing end of the strip, exerting on the coil (even when the coil is not being turned) a coiling force, when

the coil is being turned exerting on the strip between the trailing end of the strip and the coil a force acting on the strip in the direction opposite the direction of the coiling force, by said forces alone causing the strip to form a straight, even coil and when the coil is not being turned braking the strip between the trailing end of the strip and the coil to maintain the coil tight.

4. A method of forming a strip out of sheets of silicon steel comprising turning a partially formed coil of strip of previously bonded together sheets of silicon steel to continue formation of the coil, while turning the coil exerting on the strip between the trailing end of the strip and the coil a force tending to move the strip in the reverse direction and between the trailing end of the strip and the coil subjecting the strip to a stress-relieving heat treatment whereby to insure the formation of a straight, even coil.
5. A method of forming a strip out of sheets of silicon steel comprising turning a partially formed coil of strip of previously bonded together sheets of silicon steel to continue formation of the coil, while turning the coil exerting on the strip between the trailing end of the strip and the coil a force tending to move the strip in the reverse direction, between the trailing end of the strip and the coil subjecting the strip to a stress-relieving heat treatment and by said force alone causing the strip to form a straight, even coil.
